UNITED STATES PATENT OFFICE.

NATHAN M. LOWER, OF PITTSBURGH, PENNSYLVANIA.

LOCOMOTIVE STOKER.

Application filed July 22, 1919. Serial No. 312,628.

The invention relates to locomotive stokers, and more particularly to mechanism for transferring fuel from the tender to the locomotive fire box and delivering the same thereto. The object of the invention is to provide means for supplying fuel to different parts of the fire box and distribute it over the entire fuel bed and by means of mechanism which encroaches to a minimum on the restricted space in the locomotive cab.

This application is in most part a continuation of my application Serial No. 726, 108, filed October 16, 1912 (Patent No. 1,368,271, issued February 15, 1921).

In the accompanying drawings Fig. 1 is a longitudinal vertical section through stoker mechanism constructed according to the invention; Fig. 2 is a transverse section on the line 2—2, Fig. 1; showing the driving and elevating mechanism; Fig. 3 is a vertical longitudinal sectional view through one of the devices for delivering the fuel into the fire box; Fig. 4 is a horizontal section on the line 4—4, Fig. 3; Fig. 5 is a sectional view through the valve mechanism for supplying pressure fluid to the fuel delivery mechanism; and Fig. 6 is a sectional view of the means for controlling said valve mechanism, taken on the line 6—6, Fig. 2.

In the drawings the floor or deck of the locomotive is shown at 1, and a portion of the fire box at 2, the latter preferably being provided with a pair of fire door openings 3 located on opposite sides of its longitudinal center. 4 indicates the fuel hopper on the tender, for carrying the fuel to be supplied to the fire box, which fuel may be either run-of-mine coal, or fuel specially prepared before being supplied to the tender, but generally is composed of both fine and coarse particles.

The fuel passes by gravity through an opening 4^a in the bottom of the hopper 4, to a horizontal conduit 5 which is located beneath the floor of the hopper and extends underneath the deck of the locomotive. In this conduit is a rotatable shaft 6 provided with spiral vanes which form a screw conveyor 7 which conveys the fuel forwardly through the conduit toward the fire box. This conduit is provided with an abutment 8 against which the screw conveyor will crush the large lumps; also with a section 9 which telescopes into the section 10, being moved by means of the handle 11, to permit opening of the conduit to dis-

charge any large masses of slate or other hard material (described and claimed in Patent No. 1,312,858, issued August 12, 1919); and also with a rotating screen device consisting of a foraminous portion 12 which is surrounded by a foraminous sleeve 13 capable of rotatable adjustment around the portion 12 to vary the sizes of the openings through the screen, which screen serves to separate the fine from the coarse material; the fine material dropping down into an underneath conduit 15, also provided with a screw conveyor 16 which feeds the same forwardly and delivers the same through a branch conduit 17 opening through the grate of the fire box, whereby said fine material is underfed to the fire. The conveyor 16 is driven from the conveyor 7, by means of intermeshing gears 18 and 19 on the rear ends of said shafts, as shown. All of these parts, and their operation are fully described in my Patent No. 1,368,271, granted February 15, 1921, and as the present application is concerned only with the main conduit 5 and the elevating and distributing mechanism herein after described, these other parts need not be described in detail.

The fuel which is too coarse to pass through the slots in the screen is carried forward by the screw conveyor 7 to an elevating mechanism which elevates it at the rear of the fire box to the fuel delivery mechanisms, shown generally at 20 and 21, located as to inject the fuel into the fire box above the fire at a plurality of points therein. The elevating mechanism comprises a vertical conduit 21, which extends upwardly between the two fire door openings 3 and is provided with a reciprocating rod or bar 22 carrying pivoted vanes 23 which lift the fuel with a step by step movement. The rod or bar 22 is reciprocated by a link 24 connected to a crank on the worm gear 25 on the end of the shaft of the screw conveyor 7. The conduit 21 at its upper end is provided with a pair of laterally extending branches 26 which deliver to the two fuel feeding devices 20 and which have removable covers or domes 26^a, as seen in Fig. 3. In each of these lateral branches is a reciprocating rod 27 carrying a number of pivoted vanes 28, which rods are reciprocated from the rod 22 through bell crank levers 29 pivoted at 30 and each having one of its arms connected by a slot and

pin connection to the upper end of bar 22 and its opposite arm connected to a rod 27. Through this means the fuel is carried forwardly in the horizontal underneath conveyor 7, elevated to a level above that of the fire, and distributed laterally to a plurality of fuel delivery devices located at different positions laterally of the fire.

In order to vary the amount of fuel distributed to the respective fuel feeding devices, a deflecting plate 33 is located at the junction of lateral branches 26 with the vertical conduit 21, said deflector being secured to a shaft 34 which extends outwardly through the wall of the conduit and is provided with a handle 35 by means of which the position of said deflector can be varied in order to vary the amount of fuel going to the two fuel delivery devices.

The screw conveyor 7, elevator bar 22 and horizontal conveyor rods 27 are actuated from a suitable motor, such as a small rotary engine 36, provided with a speed control lever 37 and having its shaft 38 provided with a worm 39 engaging the worm wheel 25 on the screw conveyor shaft, so that all parts of the conveying mechanism are driven simultaneously from the same source.

In order to allow for the usual movements between the locomotive and tender, the rear end of the conduit 5 has a sliding connection at 41 with a frame 42 mounted to pivot at 43 on the bottom of the hopper; the vertical conduit 21 has a rotary connection at 44 with a collar on the forward end of the conduit 5; and the fine fuel conduit 15 is flexibly connected, by means of the circumferentially corrugated metal pipe 45 with the conduit 17. These features also are fully described in my Patent No. 1,368,271 above referred to.

The fuel delivery devices 20 are of a construction to not only inject the fuel into the fire box, but also to distribute it laterally therein. The particular devices illustrated in Figs. 3 and 4 are of the construction illustrated and described in my Patent No. 1,368,271 above referred to and specifically claimed in my application Serial No. 46,335 filed August 19, 1915 (Patent No. 1,368,272, issued February 15, 1921). Each of these devices comprises the hollow cylindrical casing 20^a provided with a vertically extending portion 46 through which the fuel is delivered to the casing by the conveying, elevating and distributing mechanism hereinbefore described. The fuel falls in front of the head 47 of a hollow piston 48 which slides in the casing 20^a, and is forcibly impelled into the fire box to inject a charge of fuel thereinto. The head 47 is provided with a forwardly extending scoop or shovel 49 movable on the bottom of the casing 20^a, which shovel receives the fuel and carries it during the forward movement of the piston.

The casing 20^a is provided with a passage 50 which communicates with a source of pressure, through the air or steam supply pipe 51. Said passage at its other end communicates with a space 52 within a hollow cylinder or pipe 53 attached at its outer end to the cap or head 54 which closes the outer end of the casing 20^a, and at its inner end is provided with a circular head 55 provided with a packing 56 on which the cylindrical piston 48 travels. In the retracted position of the piston, the head 47 seats against an annular surface 57 at the outer end of the pipe 53 and head 55, so as to restrict the area of the back of the head 47 against which the pressure fluid is effective in initiating the piston stroke, but as soon as the piston is moved forwardly slightly the pressure fluid is admitted to a larger area on the outer side of said piston head, whereby it is rapidly moved forwardly until the follower head 58 on the outer end of the piston reaches the cushioning space 59 on the inner face of the head 55. By this means the piston is given a sudden impulsive forward movement, which however is cushioned at the end of the stroke to prevent a heavy blow or knock.

Within the hollow space 52 is a tension spring 60 connected at one end to the piston head 47 and at its opposite end to a plug 61 threaded on an adjusting screw 62 extending through the cylinder head 54; which spring returns the piston and scoop to initial position after the delivery of each charge of fuel to the fire box, it being understood that at this time the space 52 is open to exhaust through the valve mechanism controlling the supply of compressed air to the device.

For distributing the fuel laterally over the fire bed the piston is provided with one or more laterally movable members, shown as a pair of wings or vanes 65 pivotally mounted on short shafts 66 carried by the scoop or shovel 49 adjacent the central longitudinal plane thereof. These wings or vanes are of curved shape as shown and are provided with outwardly extending arms 67 whose ends move in grooves or slots 68 in the side walls of the casing 20^a, the ends of said slots 68^a and 68^b forming abutments which engage the arms 67 and oscillate the wings or vanes on their pivots.

When the piston is in retracted position, the arms 67 engage the shoulders 68^b with the vanes in the position shown in Fig. 4, so that all or a portion of the fuel is delivered to the scoop or shovel 49 on the outside of said wings or vanes. At the end of the inward stroke of the piston or plunger the arms 67 engage the abutment 68^a with a sudden impact and hence said vanes are given a rapid swinging movement outwardly thereby impelling a portion of the fuel

sidewise and distributing it laterally toward the sides of the fire box. The inward movement of the piston also throws the fuel inwardly into the fire box so that some of it at least is delivered to the far back corners of the fire box. On the return movement of the piston the wings or vanes 65 contact against the inner end of the casing 20^a, or the wall of the fire box, which turns them sufficiently inwardly to again enter the casing 20^a, said wings being completely moved to the position shown in Fig. 4 by the engagement of the arms 67 with the abutments 68^a.

13 To assist in the lateral distribution of the fuel it may be advisable to provide a jet or jets of fluid pressure. For this purpose the head 47 of the piston is provided with a longitudinal passage 70 which communicates with a passage 71 cored out in the scoop or shovel and extending inwardly thereof and having lateral branches 72 arranged to direct two lateral jets of fluid in opposite directions. This passage is controlled by a spring-pressed valve 73 as fully described in my patents hereinbefore identified, the arrangement being such that when the piston moves forwardly fluid pressure passes through the passage 71 and is discharged through the branch passages 72. Valve 73 may have its rearward movement limited by a pin 73^a extending transversely of passage 70, as seen in Figs. 3 and 4.

35 The valve mechanism for controlling the supply of fluid pressure to the piston 47 is preferably arranged so as to produce light and heavy strokes of the piston alternately, in order to inject the fuel varying distances into the fire box during different strokes, and the strength of the spring of the valve 73 will be so chosen that upon light applications of fluid pressure to the piston said valve will not be seated, so that the fluid pressure is delivered through the lateral 45 passages 72 only upon the light strokes of the piston.

One form of suitable valve mechanism for controlling the pressure fluid to the injector so as to provide light and heavy strokes is illustrated and described in my Patent No. 1,368,271, and is illustrated in Figs. 5 and 6 hereof. This valve mechanism comprises a casing 75 which may be connected to or integral with the casing 20^a, and in which is a chamber 76 in which is slidably mounted a valve member having a stem 77 and two heads 78 and 78^a each provided with a small through leak port 79. Pressure is supplied to the chamber 76 between the heads 78 and 78^a by the supply pipe 51, and from said chamber it passes to the passage 50 through two ports or openings, marked 80 and 80^a respectively, communicating with passages leading to the passage 50. The port 80 is preferably smaller than the port 80^a. The

outer ends of the chamber 76 are closed by threaded plugs 81 having openings 82 therein, one of said openings communicating with a pipe 83 and the other with a pipe 83^a. The sliding valve mechanism is normally held in central position by two compression springs 84, located between the plugs 81 and the outer ends of the heads 78, 78^a the tension of which springs may be adjusted by screwing the plugs 81 in or out as required.

Each head 78, 78^a acts as a valve to cover or uncover its port 80 or 80^a, and the outward movement of said heads may be controlled by threaded stops 85 provided with graduated heads 86 co-operating with pointers 87 to indicate the position of said stops. By adjusting these stops the heads 78 and 78^a will uncover the ports 80 and 80^a more or less and thus enable the intensity of the different strokes of the piston 48 to be varied.

When the valve stem 77 and heads 78 and 78^a move to the left in Fig. 5, the small port or opening 80 is uncovered, which allows pressure fluid to flow from the inlet 51 to the passage 50 and thence to the fuel injecting piston, but the pressure fluid supply is restricted so that only a light stroke is produced. When the valve heads and stem move in the opposite direction, or to the right, port 80^a is uncovered, which allows a more rapid supply of pressure fluid with a correspondingly heavy stroke.

The movement of the valve stem 77 and heads 78 and 78^a may be controlled or produced in any suitable manner, but preferably by unbalancing the pressures on the outer faces of the two heads, either by diminishing the pressure effective on one head or by increasing that on the other. Fig. 6 shows one arrangement of mechanism suitable for this purpose, said mechanism comprising a casing 88 preferably open to the atmosphere through a port 89, and in which is located the rotary shaft 86 carrying a worm 91 meshing with a worm wheel 92, the shaft 93 of which is journaled in one side of the casing. One side of the casing is provided with an inwardly extending boss 94 contacting with one side face of the worm wheel 92, and provided with a through bore 95 communicating with a pipe 96^a connected to the space on the outer surface of one of the heads, say head 78. The other side of the casing 88 is provided with a rotatably adjustable member 96 whose inner end contacts with the other face of the worm wheel 92, and which has a passage 97, therethrough communicating with the space on the outside of the head 78 through the pipe 83. The worm wheel 92 is provided with a through passage 98 arranged to register alternately with the passages 95 and 97 and thereby alternately open to exhaust the chambers on the outer faces of the heads 78 and 78^a.

When the passage 98 is out of register with both of the passages 95 and 97, communication to the chambers on the outer faces of the heads 78 and 78^a is closed except through the leak ports 79, so that pressure will build up in said chambers from the supply inlet 51. Each valve head is therefore subjected to the pressure of a spring and to equal pressure on its opposite faces. so 10 that the valve mechanism shown in Fig. 5 lies in central or neutral position. Whenever the passage 98 in the worm wheel comes opposite one of the passages 95 or 97 the chamber on the outside of the corresponding 15 valve head is opened to exhaust, which allows the pressure on the inner face of said head to become effective and move the valve, thus opening one or the other of the ports 80, 80^a to the source of pressure. As soon as 20 the passage 98 moves away from its opening the pressure again builds up behind the heads 78 and 78^a and moves the valve mechanism back to normal position. The fuel injecting piston 47 then returns to normal position under the influence of the spring 60, the pressure medium behind said piston being exhausted through a passage 99 in valve head 78^a, which communicates in normal position of the valve mechanism with 25 a channel in the casing leading to an exhaust opening 100.

The rotary member 96 is held against the face of the worm wheel 92 by a compression spring 101, which produces a tight seal between said worm wheel at the open ends of the boss 94 and member 96 and prevents exhaust from the chambers of the controlling valve mechanism except when the opening 98 in the worm wheel is opposite the opening 30 in one of said members. As shown in Fig. 6 the inner end of the opening 97 in the rotatable member 96 is diametrically opposite the opening 95 in the boss 94, so that successive strokes of the fuel injecting piston 45 are produced at uniform or regular intervals. Member 96, however, is provided with an operating handle 102 by means of which it may be turned around the axis of the worm wheel 92 so that the intervals between 50 successive operations of the fuel injecting piston may be varied. By turning said member in the proper direction the time interval preceding a light piston stroke may be made shorter than that preceding a 55 heavy stroke, or vice versa. This enables a larger quantity of fuel to be collected on the piston scoop before either the light or heavy stroke, so that a larger proportion of the fuel may be fed either to the front or rear of the 60 fire box.

The mechanism described is of simple construction and occupies a minimum amount of space in the locomotive cab. The horizontal conveying conduit is located beneath 65 the locomotive cab, and there projects up

into the locomotive cab merely the single elevating conduit provided with laterally extending branches leading to the fuel delivery devices. Consequently the coal is distributed to two points laterally of the 70 fire. Furthermore the fuel delivery devices are of a construction which not only injects the fuel into the fire box, but also distributes the same laterally thereover. The curved 75 form of the wings or vanes of the distributors serves not only to throw the fuel laterally, but on account of their sweeping motion spread the fuel over a large considerable area. As a result the fuel is distributed over the entire fire bed in a substantially 80 uniform layer. The devices provide, furthermore, for controlling the amount of fuel fed to the different fuel delivery devices in order to more effectively trim the fire. 85

I claim:

1. In locomotive stoker mechanism, in combination, a fire box, a plurality of devices for feeding fuel into the fire box above the level of the fire therein, a tender having a fuel bin, a single forwardly feeding conduit receiving from said fuel bin, an upstanding elevator receiving fuel from said conduit and elevating it to a level above the fire, and laterally extending branches receiving the fuel from the upper end of said elevator and delivering it to said plurality of feeding devices. 90

2. In locomotive stoker mechanism, in combination, a fire box, a plurality of devices for feeding fuel into the fire box above 100 the level of the fire therein, a tender having a fuel bin, a single forwardly feeding conduit receiving from said fuel bin, an upstanding elevator receiving fuel from said conduit and elevating it to a level above the fire, laterally extending branches receiving the fuel from the upper end of said elevator 105 and delivering it to said plurality of feeding devices, and means for varying the relative amounts of fuel supplied to said several feeding devices. 110

3. In locomotive stoker mechanism, in combination, a fire box, a plurality of devices for feeding fuel into the fire box above 115 the level of the fire therein, a tender having a fuel bin, a single forwardly feeding conduit receiving from said fuel bin, an upstanding elevator receiving fuel from said conduit and elevating it to a level above the fire, laterally extending branches receiving the fuel from the upper end of said elevator 120 and delivering it to said plurality of feeding devices, each of said feeding devices including an oscillatory vane mounted on a vertical axis and arranged to deliver the fuel 125 into the fire box and scatter the same over the fire, and means to impart a rapid fuel impelling movement to said vane. 130

4. In a locomotive stoker mechanism, in combination, a fire box, a plurality of de- 135

vices for feeding fuel into the fire box above the level of the fire therein, a tender having a fuel bin, a single forwardly feeding conduit receiving from said fuel bin, an up-standing elevator receiving fuel from said conduit and elevating it to a level above the fire, laterally extending branches receiving the fuel from the upper end of said elevator and delivering it to said plurality of feeding devices, means for varying the relative

amounts of fuel supplied to said several feeding devices, each of said feeding devices including a horizontal oscillating delivery vane arranged to deliver the fuel into the fire box and scatter the same laterally therein, and means for imparting rapid fuel impelling movements to said oscillatory vane. 15

In testimony whereof, I have hereunto set my hand.

NATHAN M. LOWER.
